UNITED STATES PATENT OFFICE.

BANCROFT G. BRAINE, OF NEW YORK, N. Y.

GAME-BOARD.

1,009,018.

Specification of Letters Patent. Patented Nov. 14, 1911.

Application filed August 15, 1911. Serial No. 644,244.

To all whom it may concern:

Be it known that I, BANCROFT G. BRAINE, a citizen of the United States, residing at New York city, county of New York, and 5 State of New York, have invented certain new and useful Improvements in Game-Boards, fully described and represented in the following specification and the accompanying drawings, forming a part of the 10 same.

This invention relates to a playing card game board.

The invention has been made especially with the idea of providing a game board 15 which may be conveniently used in the solving of problems in various playing card games, such as bridge problems, auction bridge problems, etc.

One object of the invention is to provide 20 and certain features of the invention relate to a pocket game board for the use of travelers and others, but the game board will be found useful also for home use and may be made of such size and of such construction 25 as would make it unsuitable to be carried in the pocket.

Pocket chess boards have been made heretofore similar in some respects to the game board of this invention, but such chess 30 boards are not adapted for the purpose of the board of the present invention. The game board of the present invention is adapted for use in playing or working out various playing card games and problems, 35 and the invention includes features of construction and arrangement of the board itself and relates also to the cards or indicators used in connection with the board to represent the various cards of a deck of 40 playing cards.

A full understanding of the invention can best be given by a detailed description of 45 preferred constructions embodying the various features of the invention, and such a description will now be given in connection with the accompanying drawings, in which,

Figure 1 is a face or plan view of a game board made in accordance with the invention, opened out for playing, Fig. 2 is a section taken on line 2 of Fig. 1. Fig. 3 is a detail sectional view taken on line 3 of Fig. 1 enlarged above the size that the board will be usually made. Fig. 4 is a face or plan view of a board of modified construction. 50 Fig. 5 is a broken section on line 5 of Fig. 4. Fig. 6 is a much enlarged detail sectional

view taken on line 6 of Fig. 4. Fig. 7 is a front or face view and Fig. 8 a back view of a card or indicator such as is preferably employed with the board shown in Figs. 1 60 to 3. Fig. 9 is a face view of one form of card or indicating device for use with the board shown in Figs. 4 to 6. Fig. 10 shows in face and Fig. 11 in sectional view another form of card for use with the board shown 65 in Figs. 4 to 6. Fig. 12 shows one of the play indicators to be used on the board shown in Figs. 4 to 6.

Referring first to Figs. 1 to 3, the board 10 is formed of a sheet or sheets of leather 70 or other suitable material secured to a suitable support or back. Preferably and as shown, the board is formed of two flat parts or sections arranged to fold together along a central hinge line, the back or body portion being formed of two sheets or boards 11, 11 of suitable stiff material, such as stiff paper board, leather, or other suitable material, secured together at their adjacent edges by the covering material or otherwise so 75 as to form a hinge as indicated at 12, and each section of the back carrying a sheet 13 of leather or other suitable material which sheets 13 form the face of the board. The board will be opened out as shown in Figs. 80 1 and 2 for use and may be folded with the face of the board inside when not in use or for carrying about. The face of the board is formed with four groups of card-holding slots 15 for receiving the cards of the four 85 hands usually involved in playing card problems. These groups of card-holding slots are arranged preferably as shown, that is with two opposite groups for receiving cards representing partners' hands arranged 90 one at the right hand side of the board and one at the left hand side of the board, and with the other two groups for receiving the cards representing the hands of the opponent partners arranged one near the top 95 and one near the bottom of the board. The slots of each group are arranged in four rows or series, one for each suit, and each row will have a suitable number of slots, preferably four or more. In arranging the 100 cards of each hand in the corresponding group of slots, the cards of each suit will be placed in the slots of the row intended to receive that suit. With sixteen slots in each group, that is four slots in each of the four 105 rows, there will always be an excess number 110 of slots for each hand so that if a hand

should hold more than four cards of any one suit the excess cards of that suit may be placed in one of the rows of slots intended for one of the other suits. A greater number of slots may be provided, but the number shown is found to meet all requirements and avoids unnecessary enlargement of the board. In addition to the card-holding slots 15, the card positions for each 5 group may be marked off or otherwise indicated on the board in any suitable manner, and I prefer to mark the card positions by lines forming groups of squares, as shown, the slots being formed adjacent to the lower 10 line of each square so that when a card is inserted in a slot its exposed portion will lie over the space within the proper square. The four hands are commonly referred to as A's hand, B's hand, Y's hand and Z's hand 15 respectively, and the groups of card positions and holding slots may be so marked as shown. For each card position there is also provided as shown in these figures an additional card slot 16 extending at right angles 20 to the slot 15, so that when a card is inserted in any slot 16 its exposed portion will be over the same card position as when the card is inserted in the corresponding slot 15. When the card positions are marked by 25 30 groups of squares, as shown, the vertical slot for each square will lie adjacent to one of the side lines. It will usually be most convenient to have the vertical slots arranged adjacent to the left hand side lines of the 35 squares so that the cards when placed in these slots may be inserted from the right, but for left handed users the vertical slots may be arranged adjacent to the right hand side lines of the squares, so that the cards 40 may be inserted from the left. Adjacent to each horizontal, or suit, row of each group of card positions and slots there may be printed or otherwise applied to the face of the board the suit mark or symbol to indicate the suit to which the row is assigned. The top row of slots and positions will 45 preferably be used for cards of the heart suit, the next row for clubs, the next for diamonds and the bottom row for spades, as 50 indicated by the symbols as they appear on the drawings.

The cards or indicators to be used with the board may be of any suitable form and marking desired. The board shown is intended, however, for the use of cards or indicators 55 60 65 70 75 80 85 90 95 100 105 110 115 120 125 130 135 indicators 17 of pasteboard or other suitable thin sheet material, such as celluloid, and of substantially the shape shown, that is, of general oblong shape with one end wedge-shaped to enter the holding slots. The portion of the card which remains exposed when the wedge shaped end is inserted in any one of the slots is marked on the face side with the mark or symbol of the suit 85 to which the card belongs, and also with a

number or letter or other mark indicating the particular card of the suit. The backs of the cards are preferably marked with lines extending lengthwise of the card, or otherwise marked so that when the card is inserted face inward in any one of the holding slots the marking on the back will indicate at a glance whether the card has been inserted in a horizontal slot or in a vertical slot.

In using the game board for working out a bridge or other playing card problem, for example, the cards or indicators of each hand will be placed in horizontal slots of the group corresponding to that hand, the 75 80 85 90 95 100 105 110 115 120 125 130 135 cards of each suit being arranged in the proper horizontal row of the group. When a card is played it is removed from its slot and reversed and put back in the same slot or in the corresponding side or vertical slot. The placing of the cards when reversed in either the bottom horizontal or side vertical slots serves to indicate whether a trick was taken by A and B or by Y and Z, the placing of the reversed cards back in the horizontal slots indicating that the trick was taken by Y and Z, and the placing of the reversed cards in the side slots that the trick was taken by A and B. The tricks may be thus tallied by all four hands or by the cards 95 of only one of the four hands. For tallying with the cards of only one of the four hands, it will be sufficient to have only one of the groups of card positions provided with the vertical or side slots. Another way of tallying the tricks when all four of the groups of card positions are provided with the side slots is to place in the side slot only the reversed card of the hand that took the trick, thus showing the individual hand as well 105 as the partner hand that took the trick.

It is desirable that when the cards are inserted in the holding slots they shall be held securely enough to prevent them from falling out in ordinary handling of the game board, even when the board is turned so that the exposed portions of the cards shall extend downward from the slots in which they are inserted. To this end, in the form of board shown in Figs. 1 to 3, the holding slots 15 and 16 are cut slantingly through the leather or other material of which the face of the board is formed, such leather or other material being of sufficient thickness and body to securely hold a card which is inserted through the slot and beneath the face sheet. The face sheet or sheets 13 are pasted or otherwise secured to the back boards 11 about the portions marked for card positions and adjacent to the slots as indicated at the points *a* in order to hold the face sheet closely to the back, so that when a card is inserted in any one of the slots it will be frictionally held not only by the opposed faces of the slot but also between the face 135

sheet and the back as shown in enlarged detail Fig. 3, and so also that the card will be bent at the inner edge of the slot. The card will thus be held with sufficient security to prevent its falling out of the slot under ordinary handling of the board, and the exposed portion of the card will lie over the part of the face of the board marked as the card position and will stand out from the face of the board at an angle so as to be readily grasped for removal from the slot. The length of the slots will best be such as to limit the inward movement of the cards by engagement with the inclined or wedge-shaped wedges thereof.

When the board is made of two parts or sections to be folded together, as shown, the card positions of the groups for receiving Y's hand and Z's hand may be divided each into two sub-groups, one lying on each side of the central or fold line portion of the board, and the card positions of each said group will be marked at such a distance from the fold line or the inner edge of each board section as to provide sufficient space for the reception of the wedge shaped ends of the groups when they are placed in the inner line of said slots.

Pockets 20 formed by a band or bands set in slots in the face sheet of the board, or otherwise formed, are shown for holding the cards not in use; and the board is also preferably provided with a pocket or holding band 21 for holding slips or cuttings showing problems to be worked out, and with a memorandum sheet 22.

Figs. 4, 5 and 6 show a construction differing in some respects from the boards shown in Figs. 1 to 3 and embodying additional features of the invention. The board as shown in these figures has the four groups of card positions each with four series of card-holding slots 15 as before, but to avoid removing, turning and replacing the cards to show which cards have been played, play indicators are provided for covering or partially covering the cards which are to be considered as having been played. Such play indicators are preferably made in the form of small cards 35 having wedge-shaped lower ends for insertion in slots provided for them in the board in such position with relation to the card positions that a play indicator inserted in a slot corresponding to a card position having a card in place will lie over and cover or partially cover the card, and the play indicator cards are of such a character either by being made of transparent material or by being so shaped as not to completely cover the cards over which they are placed, as to leave the characters on the face of the card or a sufficient part thereof visible. Slots 36 for holding these play indicators are provided adjacent to and below the card holding slots 15. As

shown, the slots 36 are centered relatively to the slots 15 and the play indicators have their upper or exposed portions cut away from one side so that when placed in the slots over the cards they will cover the right hand portion of the cards, leaving the suit symbol and the card value symbol of the cards sufficiently exposed to permit the card to be readily identified. To provide for tallying the tricks, side slots 37 are also provided, one for each card holding position, so that the play indicators may be placed in either the bottom slots 36 or the side slots 37 to show which partners took the trick, and, if desired, to indicate in the manner pointed out in connection with Figs. 1 to 3 which individual hand took the trick. In order that the play may be more fully indicated, the play indicators are marked in sets of four indicators each with numbers to indicate the successive tricks. Eight such sets of play indicators numbered from 1 to 8 will usually be sufficient for card problems, but a larger number of sets or the full number of thirteen sets may be provided if desired. The board as shown is provided with pockets 38 for holding the play indicators when not in use, each pocket being supposed to hold a set of four indicators. When the slots 36 and 37 and the indicators 35 are provided for showing the cards played and tallying the tricks, the side card holding pockets 16 are of course not needed. The board as shown in Fig. 4 is also provided with individual card holding slots 39 for holding the cards when not in use, these slots being preferably arranged as shown in four horizontal rows extending across the board and close together, each horizontal row for holding the cards of a single suit.

As shown in Figs. 4, 5 and 6, also, the leather or other material forming the face of the board may be and preferably will be of less thickness than in the construction shown in Figs. 1, 2 and 3, and the card-holding slots may be cut straight through the sheet or at a less angle than as shown in Figs. 1, 2 and 3, the cards being preferably formed or provided with means to insure their being held in the slots. The card-holding slots 15 are also made with a central enlargement 40 for the purpose of receiving the small end of the card which is to be inserted in the slot and thereby enabling the end of the card to be readily entered into the slot and beneath the adjacent portion of the sheet. Cards to be used with this form of board may be formed or provided with means to prevent their falling from the slots. For this purpose the cards are formed with edge notches 41, as shown in Fig. 9, or with a holding projection or boss 42, as shown in Figs. 10 and 11, which may be formed by punching up the material of the card, or both these features might be em-

ployed together if desired. The notches 41 will be located so as to stand in the slot when the card has been inserted to the desired position, and the width of the card at the notches and the length of the slots will be such that the card will have to be slightly forced to bring the notched portion into the slot so that when a card has been so inserted it will be held against accidental displacement. When the cards are formed with holding projections or bosses 42, as shown in Figs. 10 and 11, the projection will be located so that when the card has been inserted in the slot and pushed into the desired position the projection will have been carried just beyond the under edge of the slot, as shown in Fig. 6, and will then serve to hold the card from falling out of the slot.

It is to be understood that the invention in its broader aspects is not to be limited to the precise arrangements shown of the groups of card positions and card holding slots or other card holding pockets which might be provided or to the exact constructions of the board or form of the cards as shown, but that it includes changes and modifications thereof within the claims.

What is claimed is:—

1. A playing card game board having its playing face marked to indicate card positions arranged in four groups each of which groups has a plurality of card positions for each of the four card suits, and having card holding devices for holding cards in place at the various card positions.

2. A playing card game board having its playing face marked to indicate card positions arranged in four groups each of which groups has a plurality of card positions for each of the four card suits, and having a card-holding slot for each card position.

3. A playing card game board having its playing face marked to indicate card positions arranged in four groups each of which groups has a plurality of card positions for each of the four card suits, and having a card-holding slot for each card position, and a slot for each card position for holding a play indicator.

4. A playing card game board having its playing surface provided with card holding devices arranged in four groups each of which groups has a plurality of card holding devices for each of the four card suits.

5. A playing card game board having its playing surface provided with card-holding slots arranged in four groups, the slots of each group being arranged in four rows, one for each card suit, and each row comprising a plurality of slots.

6. A playing card game board comprising two parts connected to fold together, and having its playing surface provided with card-holding slots arranged in four groups,

the slots of each group being arranged in four rows, one for each card suit, and each row containing a plurality of slots, the groups of slots being arranged with two opposite groups for receiving cards representing partners' hands arranged on opposite sides of the fold line of the board, one at the right hand side and one at the left hand side of the board, and with the other two groups for receiving the cards representing the hands of the opponent partners arranged one near the top and one near the bottom of the board, the slots forming each of these two latter groups being divided into two sub-groups, one sub-group being placed on each side of the fold line of the board.

7. A card game board having its playing face provided with horizontal card-holding slots arranged in groups, and a vertical tallying slot adjacent to each of said horizontal slots of one or more of said groups.

8. A card game board having its playing face provided with horizontal card-holding slots for the cards in play, and a slot adjacent to each of said card-holding slots for holding a play indicator.

9. A card game board having its playing face provided with horizontal card-holding slots arranged in groups, and a horizontal slot adjacent to each of said card-holding slots for holding play indicators, and a vertical tallying slot adjacent to each of said card-holding slots of one or more of said groups for holding play indicators.

10. A card game board having its playing surface provided with groups of card-holding slots for the cards to be played, and having individual card-holding slots for cards not in use, said card-holding slots for cards not in use being arranged in rows, one row for the cards of each suit.

11. A playing card game apparatus comprising a game board having card-holding slots arranged in four groups each of which groups has a series of slots for each of the four card suits, and a set of cards formed to be inserted in the holding slots and having their exposed portions marked to represent the cards of a full deck of playing cards, and means for indicating cards which have been played.

12. A card game apparatus comprising a game board having means for holding cards arranged in groups according to the hands to be played, and play indicators to extend over the cards which have been played and formed to leave the face of the cards indicated as played sufficiently visible to permit the card to be readily identified.

13. A playing card game apparatus comprising a game board having card-holding slots for the cards to be played, and having play indicator holding slots adjacent to and parallel with the card-holding slots and

other play indicator holding slots adjacent to the card-holding slots but transverse thereto, and play indicators formed to be inserted in the play indicator slots to extend 5 over cards inserted in the card holding slots to indicate cards which have been played and to show the winning cards according as they are inserted in either the slots which are parallel to or transverse to the card-holding slots.

14. A card game apparatus comprising a game board having card-holding devices for the cards to be played, and play indicators to be inserted in slots in the board to extend 15 over the cards which have been played, said play indicators being marked in sets with numbers to show the successive tricks.

15. A card game apparatus comprising a

game board having card holding slots for the cards to be played, and cards formed to 20 be inserted in said slots, and formed with means to hold them in the slots against accidental displacement.

16. Cards for use on game boards having card holding slots said cards being 25 formed with tapered ends to be inserted in the slots of the game board and provided with notched edges to hold the cards in the slots against accidental displacement.

In testimony whereof, I have hereunto 30 set my hand, in the presence of two subscribing witnesses.

BANCROFT G. BRAINE.
